UNITED STATES PATENT OFFICE.

CHARLES MORTON, OF PAWTUCKET, RHODE ISLAND.

SPINNING FRAME.

Application filed June 15, 1926. Serial No. 116,116.

This invention relates to improvements in means for driving the draft rolls in spinning frames; and the like; and has for its object to provide means whereby draft rolls may be employed of a size smaller than those ordinarily employed in machines of this character, whereby the rolls may be set more closely together to materially reduce the distance between the centers or nips of the back and front rolls and to also provide a simple and practical drive for these closely set rolls whereby an increased draft on the roving may be obtained and a relatively coarse roving used and drawn down to a relatively fine 10 yarn and at the same time produce a yarn product of uniform size and quality.

With these and other objects in view, the invention consists of certain novel features of construction, as will be more fully described, and particularly pointed out in the appended claims.

In the accompanying drawings:

Figure 1 is a side elevation showing the draft rolls in section and the arrangement of 25 frictional drive for the intermediate rolls and gearing for the whole drive.

Figure 2 is a top view illustrating the general arrangement of the rolls and the gearing for driving the same at the head end of the 30 machine.

Figure 3 is a detail showing the general arrangement of the rolls in section and showing the pair of intermediate rolls as frictionally driven by a drive roll located below them.

Figure 4 is a diagrammatic view illustrating the general arrangement of the driving gears and the intermediate rolls as being frictionally driven by a third roll.

It is found in the operation of ordinary spinning frames of this character, necessary to set the draft rolls relatively wide apart to be able to mount the driving gears on the ends thereof of sufficient size and strength to 40

operate the roll in a practical way and by this construction the distance between the centers or nips of the back and front rolls must necessarily be so great as to materially limit the amount of draft on the roving 45 thereby necessitating the use of relatively fine hanks or roving to prevent breaking down during a drawing operation or forming thick and thin places in the yarn, which renders the yarn ununiform and unsatisfactory.

The above difficulties have been overcome in 50 a practical way by the use of my improved

arrangement of mechanism which permits the use of draft rolls of a relatively smaller diameter than could heretofore be used and permits these rolls to be run very closely together and so reduce the distance between the nips or centers thereof to the very minimum. By this construction, I am permitted to employ a greatly increased draft on the roving between the back and front rolls and consequently I am enabled to use a relatively coarse hank roving. The intermediate rolls serving as a support for the roving during the drawing operation to prevent the same from breaking down thereby permitting a 60 70

fine yarn of uniform size and quality to be obtained from a relatively coarse roving and eliminating the use of the finer hank roving, thereby reducing the cost of preparing the roving, which reduction in some cases 75 reaches as high as twenty percent. In order to overcome the difficulty of driving the closely set rolls from the head end of a machine, I have positioned a third roll beneath the intermediate rolls and of a sufficient distance from the back rolls to permit it to be geared directly thereto, and I employ 80 this third roll to drive these intermediate rolls by friction, and the following is a detailed description of the present embodiment 85 of my invention and showing one arrangement of rolls and driving mechanisms whereby these advantageous results may be obtained:—

With reference to the drawings, 10 and 11 90 designate the bottom and top front rolls and 12 and 13 the bottom and top back rolls. Intermediate these two sets of rolls the intermediate rolls 14 and 15 are set, both of which are preferably of relatively small size 95 and are preferably covered with leather, these small intermediate rolls permitting the back and front rolls to be set much closer together than is usual in machines of this character.

A new feature of my present invention is my method of driving these intermediate rolls, which is that of providing a third or drive roll 16 and locating the same below this pair of intermediate rolls, the surfaces 105 of this drive roll being preferably corrugated like the lower rolls 10 and 12 and arranged to press against the leather covering of roll 15, to rotate the same.

In order to drive this roll 16, I preferably 110 mount a gear 17 on the back roll 12 to mesh directly with the gear 18 on this drive roll

16, whereby this drive roll is caused to rotate in a direction opposite to that of the roll 12, its surface thus coming in contact with the roll 15 causes the latter to rotate 5 in a direction corresponding to that of the back roll to assist in advancing the roving being acted upon.

In driving all of these rolls at the required ratio, I mount the large drive gear 19 on the 10 end of the front roll shaft 20 outside of the bearing stand 21 and between this stand and the frame 30 I mount a pinion 22 which meshes with the intermediate larger gear 23 supported on the short shaft in the swinging 15 or adjustable bracket 24. On the end of this shaft I mount a pinion 25 which meshes with the larger gear 26, this gear being mounted on the jack shaft 27 and is arranged to drive the back roll through pinions 28 and 29.

By this arrangement of mounting the drive roll 16 below the intermediate draft rolls 14 and 15, I am enabled to position the drive roll between the back roll and the intermediate roll and space the same sufficiently to permit the use of gears 17 and 18 of a size to well perform this driving function and at the same time I am enabled to place the front and back draft rolls sufficiently close together to obtain the desired short distance between their nips.

When it is desired to change the speed of the back roll relative to that of the front roll, it is only necessary to change the size 35 of pinion 25, which can be done by swinging the bracket arm 24 on its bearing 21 into position to cause the fresh pinion to again properly mesh with the gear 26 and it will be seen by this arrangement that any relative change in speeds of the back roll will 40 also make a corresponding change of speed in the intermediate rolls 14 and 15.

By this construction and arrangement of gearing, it is obvious that I may reduce the 45 distance between the nips of the front and back rolls 10 and 12 to the very minimum and use the middle rolls as a carrier only, if desired. In other words, by having the rolls widely spaced a relatively fine hank 50 roving must be employed to produce a yarn of a given size and quality, but by reducing the space between the nip of the rolls, a greater draft may be employed without breaking down the roving and I am thus enabled to produce the same quality and size 55 of yarn from a much coarser hank roving thus eliminating one distinct step in operation which has heretofore been necessary to reduce the roving from the coarse hank to 60 the fine hank size in order to obtain a satisfactory even yarn, by which arrangement I obtain a material saving in the cost of 65 yarn production which in some cases figures as high as twenty per cent.

65 I have shown and described my improved

roll driving mechanism as applied to a spinning frame, but it is understood that the same may be employed if desired on any other machine having rolls employed in the drafting of textile fibers.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a spinning frame, front and back sets of draft rolls, gears for driving said sets of rolls at different predetermined speeds, a set of intermediate rolls set adjacent both said back and front rolls, and means set to frictionally engage and drive only said intermediate rolls.

2. In a spinning frame, front and back draft rolls, gears for driving said rolls at different predetermined speeds, a set of intermediate rolls set adjacent both said back and front rolls, a drive roll arranged to frictionally drive said intermediate rolls only, and gears for driving said friction roll.

3. In a spinning frame, front and back draft rolls, gears for positively driving said sets of rolls at different predetermined speeds, a set of carrier rolls intermediate said front and back rolls, a roll having a friction driving surface set to engage and drive only said intermediate rolls, said friction drive rolls being geared to said back rolls.

4. In a spinning frame, front and back draft rolls, gears for driving said sets at different predetermined speeds, a set of carrier rolls intermediate said front and back rolls, a corrugated roll geared to one of said back rolls and set below said intermediate rolls and having an extended engaging surface arranged to act upon and frictionally drive said intermediate rolls at a surface speed greater than that of the back rolls.

5. In a spinning frame, front and back draft rolls, gears for driving said rolls at a predetermined ratio, a set of intermediate rolls set with their fiber-engaging surfaces adjacent both said back and front rolls and a gear driven friction drive roll below said intermediate rolls for driving said rolls in a direction to advance the roving.

6. In a spinning frame front and back sets of draft rolls, means for driving said sets at different relative speeds, a set of intermediate rolls between said sets of back and front rolls and positioned with their working surfaces to run just clear of those of said back and front sets of rolls, and a draft roll positioned to frictionally engage and drive said intermediate set of rolls.

7. In a spinning frame front and back sets

of draft rolls, means for driving said sets at different relative speeds, a set of intermediate rolls between said sets of back and front rolls and positioned with their working surfaces to run just clear of those of said back and front sets of rolls, and a gear driven roll arranged to engage and drive said intermediate set of rolls by friction.

8. In a spinning frame front and back sets
10 of draft rolls, means for driving said sets at different relative speeds, a set of intermediate rolls spaced substantially equally distant between said back and front rolls, said sets of rolls being so positioned relative to
15 each other that their working surfaces run

just clear of each other, and a drive roll positioned to frictionally engage and drive said intermediate set of rolls.

9. In a spinning frame front and back sets of draft rolls, means for driving said sets at different relative speeds, a set of intermediate rolls spaced substantially equally distant between said back and front rolls, said sets of rolls being so positioned relative to each other that their working surfaces run
20 just clear of each other, and a roll arranged to drive said intermediate set and said drive roll being geared to said back rolls.
25

In testimony whereof I affix my signature.
CHARLES MORTON.
